PATTERN WHEEL ASSEMBLY

Harry Agulnek, Brooklyn, N. Y., assignor to
 Samuel Mishcon, doing business as Supreme
 Knitting Machine Co., Brooklyn, N. Y.

Application April 21, 1934, Serial No. 721,711

5 Claims. (Cl. 66—50)

This invention relates to jack pattern wheels, particularly of the type used on circular knitting machines for producing knitted pattern designs, one of the main objects of the invention being to permit the use of such a wheel with a relatively small or fine gauge cylinder, or one having more needles per inch than can generally be used according to the present practice.

The usual type of jack pattern wheel contains a plurality of circumferentially disposed slots between which are inserted jacks for operatively engaging the butts of the needles to produce predetermined knitted patterns. Inasmuch as the walls of these slots are generally integral with the wheel proper, there is always a minimum limitation to the pitch of these slots, due to the fact that the walls cannot, for practical reasons, be made too thin. Should thin walls be produced by precision machining, or otherwise, there is always the danger of bending, breaking or distorting these walls, thereby rendering the wheel inaccurate or entirely useless for its purpose, and necessitating frequent replacements thereof. It is hence one of the objects of my invention to overcome this disadvantage by the use of independent walls inserted into appropriate circumferentially positioned slots in the pattern wheel, whereby the wheel becomes a housing both for these walls, and for the jacks. Specifically, the walls are inserted in the wheel in such a way as to permit the placing of a jack between adjacent walls, thereby enabling the wheel to serve its operative purpose in the usual way, and at the same time permitting a greater number of walls and jacks to be circumferentially positioned around the pattern wheel than is otherwise possible. With the use of the thin steel walls I employ in my invention, a smaller pitch can be obtained, enabling the wheel to operate with as many as thirty needles per inch as compared to a maximum of twenty-two in the ordinary type of wheel over which this invention is an improvement. As these walls are preferably made of spring steel, they can withstand a certain amount of flexing and bending, without interfering with the operation of the wheel; and should a wall become mutilated or distorted, my invention provides, in one modification thereof, a method of removing the defective wall and replacing it with a new one.

In the old form of wheel, the inclination thereof is generally less than 40° ,—a necessary condition in view of the required thickness of the walls forming the slots and the resultant minimum limitation to the number of needles per inch with

which the wheel could operatively coact. Such a small angle produces relatively small successive elevations or steps between adjacent walls, making the operation not very positive, and resulting frequently in errors. With the use of my invention, however, a greater angle, and hence a larger wheel can be employed, thereby providing not merely a smaller pitch, but also larger steps between adjacent walls, to effect more positive engagement of the jacks and needle butts.

It is the general practice in producing a Jersey stitch, or one where all the needles are completely elevated, to have a cam with its working face angularly disposed with reference to the butts of the needles and adapted to elevate them to their uppermost positions during the rotation of the machine, in this way eliminating any design produced by the operation of the jack pattern wheel. This frequently necessitates the temporary removal of the pattern wheels during this operation,—thereby frequently causing the walls, when reinserted in position, to be out of time with the needles. To overcome this disadvantage, I have conceived a lifting cam positioned adjacent the pattern wheel, and so designed as to permit, either by automatic or manual operation, the elevation of the needles into their uppermost projected positions, without disengaging the pattern wheel from the needles, and in this way keeping the wheel constantly in time and always in engagement with the needles. This lifting cam has the further advantage of being firmly set in its upper or operative position without the danger of having a tight needle push it down to its inoperative position, thereby eliminating the danger of errors from this cause.

Other objects, features and advantages will appear from the drawings and the description hereinafter given.

Referring to the drawings,

Figure 1 is a front diagrammatic view showing a section of the cylindrically disposed needles and illustrating the relative positions of the pattern wheel and the lifting cam.

Figure 2 is a fragmentary section of Figure 1 taken along line 2—2 showing in detail the preferred form of pattern wheel constituting part of this invention.

Figure 3 is a diagrammatic view looking from the cylinder outwardly, showing the relative positions of the needle butts, pattern wheel walls and jacks.

Figure 4 is a diagrammatic view showing a portion of the needle butts coacting with the walls and jacks of an angularly disposed pattern wheel

(shown by dot-dash lines), a number of the walls and jacks being shown in their circumferential and substantially radial positions, the jacks being on the upper surface and the walls on the lower surface of the wheel.

Figure 5 is a detached view of the parts constituting the assembly of pattern wheel cover (a fragment being shown), a jack, the pattern wheel body (a fragment being shown), and a wall, these parts being illustrated from the top downwardly in the order herein given.

Figure 6 is a side view of the detached arrangement of Figure 5 showing the relative angular positions of the parts of Figure 5.

Figure 7 is a diagrammatic view of a fragment of the pattern wheel, showing the slots, the walls inserted therein, and jacks therebetween.

Figure 8 is a fragmentary section similar to Figure 2, showing a modified form of my invention where both the walls and jacks are inserted on the upper surface of the pattern wheel proper.

Figure 9 is a view similar to Figure 7 showing the relationship of slots, walls and jacks of the device of Figure 8.

Figure 10 is a view similar to Figure 1, showing a fragmentary section of the lifting cam assembly.

Figure 11 is a side sectional view of Figure 10 along line 11-11.

Figure 12 is a perspective of the lifting cam proper.

In the drawings, and particularly in the preferred embodiment thereof, the jack pattern wheel 15 contains a plurality of circumferentially disposed slots 16 within which are inserted the relatively thin walls 17 preferably made of spring steel. The said slots communicate with recessed portion 18 which contains a circular groove or notch 19 extending upwardly into the body of the wheel; and the said walls are adapted to fit into said recessed portion, the extension 20 of the wall entering into and being adapted for accommodation by said notch 19, thereby providing a well secured fit for the walls. In between the outwardly projecting terminal portions 21 of the walls are positioned the jacks 22, arranged for operative engagement with the butts 23 of the needles 24. The said walls 17 can be secured into place by soldering, or removably inserted by a forced fit, or in any other suitable manner.

With this arrangement it will be seen that with the machine rotating in the direction of the arrows A (Figure 3), the pattern wheel 15 will rotate obliquely with respect thereto in the direction of arrow B, the butts 23 of the needles intermeshing with said outwardly projecting portions 21 of the walls 17 to cause this movement. Wherever there is a jack between the walls, it will engage the needle butt intermeshing with the walls between which the jack is positioned,—thereby causing an upward movement of the needle during the operative rotation of the pattern wheel. In this way designs are produced in accordance with predetermined settings of the jacks.

Inasmuch as the walls 17 contain no portion thereof extending over and upon the upper surface of the pattern wheel 15,—(the body portions of the walls extending underneath the wheel into the recessed portion 18),—the inner portions 25 of the jacks are not crowded due to their radial arrangement, thereby leaving room for more jacks operatively applied to the wheel. In other words, had the jacks and walls both been positioned along the upper surface of the pattern wheel,

there would be a congestion of jacks and walls along the interior portion of the wheel.

It will also be noticed that inasmuch as the walls 17 are relatively thin, the angle of the pattern wheel with respect to the horizontal can be made sufficiently great to provide for the operative engagement of the walls with needles relatively close together. Having this greater angular disposition, it will be seen, particularly by referring to Figure 3, that there are larger successive steps between walls, thereby effecting a more positive and accurate operative contacting of the parts.

Each pattern wheel is preferably provided with a cover plate 26 suitably bolted or otherwise secured in place, said plate containing a plurality of teeth 27 which intermesh with the inserted walls 17 of the housing. This arrangement not only reinforces the walls and firmly holds them and the jacks in place, but serves also to properly space and align the walls for operative conditions.

Figure 8 shows a modification wherein both the jacks 28 and walls 29 are inserted into the upper surface of the pattern wheel 30. With this design, either an elevated boss or a plate 31 is employed to serve as an abutment for the jacks and walls. A cover plate 32, similar to that shown in the preferred embodiment of my invention, can also be used with this modified form thereof, the teeth 33 intermeshing with the walls 29 positioned around the wheel. Figure 9 shows in diagrammatical form a top view illustrating the relative positions of jack, walls and slots 34 circumferentially positioned around this modified form of pattern wheel.

The lifting cam arrangement that I employ in conjunction with the pattern wheel is illustrated in Figures 10, 11 and 12. The cam proper 35 is slidably movable in a vertical direction within a suitably positioned slot, the oblique face 36 thereof being operatively engageable with the butts of the needles to raise them to their uppermost levels when the cam is in its upper projected position. The cam is provided with a horizontal slot 37 adapted to slidably and rotatably receive 40 the pin 38 eccentrically positioned on and extending rearwardly from the rear face of the shaft 39 which extends forwardly from its housing 40 to permit rotation thereof by a manual manipulation of the knurled knob 41. The said shaft 39 contains two oppositely positioned flat portions 42 and 43, each being adapted to successively receive the plunger 44 constantly urged upwardly thereagainst by the helical spring 45. The screw member 46, abutting against the spring, can be manipulated for varying the tension therein.

By turning the knob 41 until the flat portion 43 of the shaft enters into operative engagement with the plunger 44, the pin 38 will be in its uppermost position,—the said pin during its upward rotary movement engaging the upper wall of slot 37 to upwardly actuate the cam 35, thereby moving the butt-engaging face 36 thereof upwardly, and the needles consequently out of the positions they have assumed as a result of the operation of the pattern wheel. Inasmuch as the pin 38 is in dead center at its uppermost point, and the spring 45, the plunger 44 and surface 43 cooperate to hold the shaft 39 firmly set in position, the cam will remain in its uppermost position until released therefrom by a further manipulation of the knob 41, such as by a rotation thereof until the flat surface 42 engages the plunger 44 to bring the pin to its lowermost position. Hence it is apparent that once the cam is 75

in its upper projected position, no tight needle will be able to force the cam downwardly at unwanted times. Of course, it is understood that instead of manipulating the knob 41 by hand, 5 automatic mechanical means can be employed to accomplish the same purpose.

Another advantage of this form of lifting cam is that the needle is gradually lifted to its uppermost position due to the eccentric position 10 of the pin 38, thereby obviating the danger of damage to the needle such as would occur in the event of a sudden upward snap thereof.

It is understood that various other mechanical forms and modifications of this invention besides the embodiments thereof hereinbefore 15 described can be employed within the scope of the appended claims.

What I claim is:

1. In a pattern wheel of the class described, a plurality of suitably secured, circumferentially disposed, spaced walls, each of said walls having an outwardly projecting terminal portion extending above the upper surface of said wheel and an inwardly projecting portion extending along the 25 underside of the wheel, a predetermined number of jacks radially positioned upon the upper surface of the wheel and extending beyond the periphery thereof, the outer ends of each of said jacks being flanked by two adjacent terminal portions of said walls, the spaces between the extreme inner portions of the jacks being entirely unobstructed, and means for holding said walls and jacks in place.

2. In a pattern wheel of the class described, a plurality of peripherally disposed, spaced slots, a circular recessed portion on the underside of said wheel and which communicates with all of said slots, a circular groove extending from said recessed portion upwardly into the body of the 35 wheel, a relatively thin wall inserted in each of said slots, each of said walls having an outwardly projecting terminal portion extending above the upper surface of the wheel and an inwardly projecting portion extending into said recessed portion and having an inner terminal extension entering into said groove whereby the

said walls are held against longitudinal movement, a predetermined number of jacks inserted between the said outwardly projecting terminal portions of certain of said walls and positioned along the upper surface of the wheel, and means 5 for holding said walls and jacks in place.

3. In a pattern wheel of the class described, a plurality of independent, peripherally disposed, spaced walls adapted to accommodate independently removable jacks therebetween, a cover 10 plate containing a plurality of peripherally disposed teeth corresponding in number and pitch to said walls, said plate being in engagement with the upper edges of said jacks to hold them in place, the said teeth intermeshing with the outer 15 terminal portions of said walls, and means for securing said plate to the wheel.

4. In a pattern wheel of the class described, a plurality of suitably secured, circumferentially disposed spaced walls, each of said walls having an outwardly projecting terminal portion extending above the upper surface of said wheel and an inwardly projecting portion extending along the underside of the wheel, said wheel containing a circular groove on the underside thereof, each 20 of said walls having its inner extremity provided with an angularly disposed extension entering into said groove to be held by the sides thereof against longitudinal movement, a predetermined number of jacks inserted between the said terminal portions of certain of said walls and positioned along the upper surface of the wheel, and means for holding said walls and jacks in place. 25

5. In a pattern wheel for knitting machines, a plurality of radially disposed jacks positioned 35 upon the upper surface of the wheel and extending beyond the periphery thereof, a plurality of circumferentially disposed spaced walls in interlocking engagement with the underside of the wheel and containing upwardly extending 40 terminal portions outside of the periphery of the wheel proper, certain of said terminal portions containing therebetween the outer ends of said jacks.

HARRY AGULNEK. 45
